Bohleberg & Seelbether
ATTORNEY

UNITED STATES PATENT OFFICE.

THOMAS W. KIRKMAN, OF NEW YORK, N. Y.

LOUD-SPEAKER CASING.

Application filed January 17, 1924. Serial No. 686,857.

To all whom it may concern:

Be it known that I, THOMAS W. KIRKMAN, a citizen of the United States, residing at New York, in the county of New York and State of New York, have invented certain new and useful Improvements in Loud-Speaker Casings, of which the following is a specification.

This invention relates to a loud speaker 10 casing, the primary object of which is to construct the same from parts, all of which have been stamped from sheet metal. One of the chief sources of loud speaker trouble is due to the fact that the cover is removed 15 by amateurs with a view of inspecting the interior thereof. It is therefore one of the features of my invention to provide a suitable seal against tampering and to so locate this seal that it will not be visible.

Other objects, features, and advantages 20 will more fully appear from the detailed description below taken in connection with the accompanying drawings in which.

Fig. 1 is a vertical section of the device 25 taken through the seal.

Fig. 2 is an enlarged view taken on the line 2—2 of Fig. 1.

Fig. 3 is an enlarged view of the seal 30 together with the mold for forming the same.

Fig. 4 is a sectional view of the mold for the seal.

Referring to the drawings in detail, the reference numeral 10 designates a cup preferably of cylindrical shape provided with a side wall 11, a bottom 12 and a flange 13 projecting laterally from the upper edge of the side wall 11. The bottom is provided with a central screw threaded opening 14 to receive the post (not shown) for supporting one form of mechanism to be housed in said casing. The bottom is also provided with perforations 15 and 16 for receiving the binding posts. The side wall 11, bottom 12 and flange 13 are preferably stamped up from a single sheet of material.

The cup is provided with a cover 17 comprising the horizontal portions 18 and 19, a skirt 20 telescoping over and projecting 50 downwardly beyond the flange 13 and a central tubular member 21 adapted to receive the amplifying horn of the instrument. Secured between the horizontal portion 19 of the cover and the flange 13 of the cup is the usual diaphragm 22.

For securing the cover 17 to the cup 10 I preferably employ a plurality of bolts 23 (only one being illustrated), which pass through the horizontal portion 19 of the cover and are screw threaded to the flange 60 13 of the cup. The screw threaded end of one (or more) of these bolts may be equipped with a slot 24. The lower projecting end of each bolt 23 is located between the skirt 20 and the side wall 11 of the cup 10. This 65 construction enables a suitable seal 25, clearly illustrated in Fig. 3, to be molded over the lower screw threaded end of the bolt so as to prevent the cover 17 from being removed or tampered with without leaving 70 evidence thereof. The sealing material employed, preferably lead, being molded over the screw threaded end of the bolt 23, the latter cannot be turned without removing 75 the seal. If the slot 24 is provided the seal is actually destroyed. The seal 25 is formed by a mold 26 preferably circular in shape, the bottom of which, is provided with suitable dies for stamping on the seal any suitable indicia.

To the bottom of the cup 10 is secured, preferably by a plurality of rivets 27, a suitable base 28 comprising upper and lower telescoping shell members 29 and 30, each of which is stamped up from a single sheet 80 of material. The upper shell member 29 which is in the form of an inverted cup, preferably comprises a horizontal portion or bottom 31 resting against the bottom 12 of the cup 10, a portion 32 projecting downwardly from the portion 31, a portion 33 extending horizontally from the portion 32 to form a ledge and a second downwardly extending portion 34 constituting a peripheral flange. The lower shell member 30, 85 which also is in the form of an inverted cup, comprises a flat portion or bottom 35 resting against the flat portion 31 of the upper member, the portion 36 projecting downwardly to a point substantially in a plane 90 with the lower edge of the flange 34, a portion 37 extending laterally from said point to the flange 34 and an upwardly projecting flange 38 telescoping within the flange 34.

The shell members 29 and 30 are equipped 100 with central perforations to receive the boss 39 of the cup 10 and are also provided with perforations 40 and 41 registering respectively with the openings 15 and 16 in the bottom 12 of the cup. These openings 110

15, 16, 40 and 41 are adapted to receive binding posts with which practically all speakers are equipped.

The part 33 of the upper shell 29 form a ledge for the base, while the portion 37 of the shell 30 constitutes a rest to which the felt ring or other suitable pad 42 is attached, the purpose of which will be understood.

10 From the foregoing, it will be seen that I have devised a simple housing or device for containing the operative elements of a loud speaker apparatus, all of the parts of said housing, and particularly the base thereof, being stamped up from suitable material with the result that the cost of manufacture of the same is reduced to the minimum. The base is so constructed as to elevate the cup 10 to the required height, 20 it being understood that the horizontal portions 31 and 35 of the shell portions 29 and 30 may be located at any distance from the ledge portion 33 and the rest portion 37 by shaping the dies in accordance 25 with the demands required in this connection.

I have herein illustrated and described what I now consider the preferred form of my invention, but it is to be expressly understood that I do not limit myself thereto as many changes may be made in points of detail and other embodiments resorted to without deviating from the true spirit and scope of my invention as defined by the 35 annexed claims.

What I claim is:

1. A loud speaker casing comprising a cup portion and a cover portion secured thereto, in combination with a base therefor comprising two companion members secured to the cup and each of which is stamped from a single sheet of material, the upper member comprising two elevated portions one of which defines a ledge and the other of which provides a surface upon which the cup is supported, and the lower member comprising an elevated portion, a flat portion to form a rest, and an upwardly projecting annular flange telescoping into the upper member.

2. A loud speaker casing comprising a cup adapted to contain sound reproducing mechanism, said cup being open at its top, a cover secured to the cup and closing the top thereof, said cover being designed for direct connection to sound amplifying means, and a support for the cup attached to the bottom thereof, said support comprising upper and lower shell members interfitting with each other and each stamped up from a single sheet of material.

3. A loud speaker casing comprising a cup-shaped part open at its top and having a flat bottom, a cover secured to said cup-shaped part to close the top thereof,

and a support attached to the bottom cup-shaped part, said support comprising upper and lower telescoping shell members each of which is stamped up from a single sheet of material.

4. A loud speaker casing comprising a cylindrical cup open at its top, a cover closing the top of said cup, and means for supporting the cup comprising an upper shell member having a depending peripheral flange and a lower shell member having an upstanding peripheral flange telescoping snugly within the said peripheral flange of the upper shell member.

5. A loud speaker casing comprising a cup, a cover secured thereto, and a support for the cup secured to the bottom thereof and comprising upper and lower shell members, each of which is stamped up from a single sheet of material, said upper shell member being in the form of an inverted cup and having a peripheral ledge intermediate of its top and bottom, and said lower shell member being provided with a horizontal rest portion and an upstanding flange surrounding said rest portion and fitting snugly within the open end of the upper shell member.

6. A support for a loud speaker cup or the like comprising an upper shell member and a lower shell member each of which is stamped up from a single piece of material, the upper member having two elevated portions one of which defines a ledge and the other of which provides a cup-supporting surface and the lower shell member being provided with an elevated portion, a flat portion to form a rest and an upwardly projecting annular flange telescoping into the upper shell member.

7. In a loud speaker casing, a cup formed of a single sheet of material and comprising a perforated bottom, a side wall of cylindrical shape, and a flange projecting laterally from the upper edge of said side wall, and a cover formed of a single sheet of material and comprising a portion adapted to rest upon the said flange, and a skirt telescoping over and projecting downwardly from the peripheral edge of said flange, means passing through said flange and the portion of the cover resting thereon for securing said cover to said cup, and a seal for said securing means located between said skirt and the side wall of said cup.

8. In a loud speaker casing, a cup stamped from a single sheet of material and comprising a perforated bottom, a side wall of cylindrical shape, and a flange projecting laterally from the upper edge of said side wall, a cover stamped from a single sheet of material and comprising a portion adapted to rest upon the said flange, and a skirt telescoping over and projecting downwardly

- from the peripheral edge of said flange, means passing through said flange and the portion of the cover resting thereon for securing said cover to said cup, and a seal 5 for said securing means located between said skirting and the wall of said cup.
9. In a loud speaker casing and support, a cup stamped from a single sheet of material and comprising a perforated bottom, a 10 side wall of cylindrical shape, and a flange projecting laterally from the upper edge of said side wall, a cover stamped from a single sheet of material and comprising a portion adapted to rest upon the said flange, 15 and a skirt telescoping over and projecting downwardly from the peripheral edge of said flange, means passing through said flange and the portion of the cover resting thereon for securing said cover to said cup,
- 20 and a base comprising two interfitting members each stamped up from a single sheet, the upper one of which comprises a flat portion of substantially the same diameter as the bottom of said cup, a portion projecting 25 downwardly therefrom, a portion constituting a continuation of and extending laterally from said downwardly extending portion, and a fourth portion forming a continuation of and extending downwardly from 30 the third mentioned portion to form a peripheral flange, and the lower of said interfitting members comprising a flat portion normally resting against and secured to the flat portion of said upper interfitting member, a portion biased downwardly and outwardly to a point in a plane with the lower edge of the flanged portion of said upper interfitting member, a third portion extending laterally from said point to the flanged 35 portion of said upper portion and thence upwardly to form a flange which telescopes with the flange of the upper member.
10. Supporting means for a loud speaker cup or the like comprising an upper, inverted, cup-shaped base member having a depending peripheral flange, the bottom of said member forming a loud speaker cup supporting surface, and a lower base member having an upstanding peripheral flange 45 fitting snugly within the lower, open end of the upper base member, each of said base members being formed from a single piece of material.
- 50 11. Supporting means for a loud speaker cup or the like comprising an upper inverted cup-shaped base member, the bottom of said member forming a loud speaker cup supporting surface, and a lower inverted cup-shaped base member having its bottom
- in engagement with the bottom of the upper 60 base member and provided with a peripheral extension on its open end fitting snugly within the open end of the upper base member, each of said base members being formed from a single piece of material. 65
12. A device for supporting a loud speaker cup or the like comprising upper and lower shell members, telescoping with each other, each of said members being formed from a single sheet of material, said 70 upper shell member being formed at its upper end with a central, cup-supporting portion and a lower, open-ended base portion of a diameter greater than that of its supporting portion, and said lower shell 75 member being located within the open-ended portion of the upper member and having an upstanding peripheral flange fitting snugly therein.
13. In a device of the character described, 80 a cup or similar member having a peripheral flange, a companion member having an annular portion resting upon said flange and also having a skirt telescoping over and projecting downwardly from the peripheral edge 85 of said flange, means passing through said flange of the one member and the annular portion of the other member for securing the same to each other, and a seal molded over the end of said means. 90
14. A loud speaker casing comprising a cup having a flange at its top, a diaphragm, a cover, and means for securing said cup, diaphragm and cover to each other comprising screws passing through the cover, diaphragm and flange into screw threaded engagement with said flange, and a seal molded over the projecting end of one or more of said screws. 95
15. A loud speaker casing, comprising a 100 cup having a flange at the top thereof, a cover having a horizontal portion in juxtaposition to said flange and having an apron extending over and downwardly from the periphery of said flange, a diaphragm located 105 between said cup and cover and engageable by said flange and said horizontal portion of the cover, and means for securing said cup, cover and diaphragm comprising one or more screws passing downwardly through 110 said horizontal portion of the cover, the diaphragm and the flange, and a seal molded over one or more of the projecting ends of said screws and located between said apron and the cup. 115

In testimony whereof I affix my signature.

THOMAS W. KIRKMAN.
